UNITED STATES PATENT OFFICE.

WILLIAM PROVINES, OF COLUMBIA, MISSOURI.

UTERINE SUPPORTER.

Specification of Letters Patent No. 15,897, dated October 14, 1856.

To all whom it may concern:

Be it known that I, WILLIAM PROVINES, of Columbia, Boone county, State of Missouri, have invented a new and Improved Mode 5 of Making Uterine Supporters; and I do hereby declare that the following is a full and exact description thereof, reference being had to the accompanying drawings and to the letters of reference marked thereon.

10 The nature of my invention consists in providing an air tight bag somewhat spherical in form of suitable size and thickness, this bag is to be made of india rubber or other substance or substances having the

15 properties of impermeability and pliancy so that when inflated it will retain air and constitute a cushion or supporter, the opening in which is secured by a mouth piece made as follows: The mouthpiece (Figure 2) is composed of two tubes or short cylinders having to one end of each affixed a convex or trumpet shaped disk, these tubes are placed one within the other and held in position by means of a screw cut in each (male and female). The female tube and disk are placed within the bag, the disk immediately 20 behind the margin of the opening; into this is inserted the male tube, the disk of which remains outside the bag. When these tubes are screwed tightly together, the margin of the opening in the bag is secured between the two disks or plates and made air tight.

25 Figs. 1 and 2. To complete the mouth-piece a valve Fig. 2 is so placed as to secure

the opening in the male tube inside at or 35 near the top, making it also air tight. The outer plate Fig. 1 is provided with a notch on each side of the opening to receive two corresponding projections on the point of the syringe or elastic tube; these serve to hold the instrument (supporter) steady 40 while receiving the air.

Method of using.—The supporter in a flacid state is placed in position and readily inflated to any required degree of tension by 45 means of a flexible tube or syringe, through which the air may be forced into it, Fig. 2. The valve inside will in either case retain the air. The instrument may be removed at pleasure by introducing a blunt point into 50 the external opening in the mouth piece a sufficient distance to raise the valve and suffer the air to escape. This opening will be readily found, being retained in position by 55 the greater weight of the mouthpiece.

Advantages.—This instrument is easy of application and removal, renders local medication easy, is very adjustable, and will furnish an easy elastic support promotive of 60 comfort to the wearer.

I claim—

The combination of the ball and the valve apparatus described in the manner and for the purposes set forth.

WILLIAM PROVINES.
